UNITED STATES PATENT OFFICE

2,007,307

POWER HAMMER

John Sack, Scranton, N. Dak.

Application June 1, 1933, Serial No. 673,925

1 Claim. (Cl. 78—40)

My invention relates to certain new and useful improvements in power driven hammers for various uses and purposes and the invention has for an object to provide a very simple and inexpensive construction which will readily and effectively serve its intended purposes.

Further, the invention has for an object to provide a beam hammer, the strokes of which may easily be adjusted for thicker or thinner work.

Further, it is an object to provide a power hammer in which the hammer proper is so mounted as to avoid side friction such as is usually caused by the use of short connecting rods.

Further, it is an object to provide a power hammer in which the hammer proper is supported on balanced or equalized pressure arms with which the connecting rod from the crank shaft is joined, thereby yieldingly mounting the hammer to dampen the rebound shocks on the hammer reciprocating mechanism.

Further, it is an object to provide a power hammer and anvil cooperating therewith whose impacting dies are removable.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claim, reference being had to the accompanying drawings, in which:—

Figure 1 is a front elevation of the invention.

Figure 2 is a side elevation thereof.

Figure 3 is a horizontal section on the line 3—3 of Figure 2.

Figure 4 is a detail elevation of a modified construction of hammer carrying lever device.

Figure 5 is a similar view of a further modification.

Figure 6 is a detail perspective view of the hammer carrying lever guide or cross head.

In the drawings in which like numerals of reference indicate like parts in all of the figures, 1 represents a suitable base from which extends upwardly a pair of side plates 2 and at a suitable distance from the base there is located between the side plates an anvil post 3, the same being secured to the side plates by cross bolts 4.

Angle irons 5 are riveted at 6 to the upright side plates 2 and are connected by bolts 7 to the base 1.

On suitable angle iron brackets 9, bolted at 11

to the side plates 2, are bearings 8 for the crank shaft 12, the bearing 8 being bolted at 10 to the angle brackets 9.

The crank shaft 12 carries a fly wheel 13. There is also a drive pulley 14 rotatably mounted on the crank shaft by means of suitable thrust and anti-friction bearings 15, the pulley 14 having a clutch face 16 to cooperate with the shiftable clutch 17 that is keyed to the crank shaft and is provided with a shifting collar 18 to be engaged by the fork of the clutch shifter bell crank 19. The clutch is kept out of engagement normally by a pull back or clutch throw-out spring 24 operating via the lever 19. The lever 19 is mounted on a suitable bracket 20 and is pivoted thereto at 21. It may be operated to throw in the clutch by means of a pedal 22 and connecting rod 23 as shown.

25 is the connecting rod between the crank of the crank shaft and the cross head 55 of the hammer-carrying spring lever device. The lower end of the connecting rod 25 has a bearing 27 for the crank of the crank shaft 12 and the upper end is pivotally secured at 37 to the bearing lugs 36 of the cross head 55 hereinafter again referred to.

It will be observed that a center line runs through the anvil 3 and the hammer proper 52 will also pass through and lie normal to the axis of the crank shaft. The connecting rod 25 has its ends bent so that the main part of the rod may lie to one side of the center line of the hammer and anvil as best indicated in Figure 2. Where the connecting rod 25 passes through the rear plate 29 that plate is vertically slotted as at 38.

The rod 25 may be made in two lapped sections, if desired, joined together by bolts passing through certain ones of a series of bolt holes in the lapped ends as at 26, see Figure 2.

28 designates the front hammer guide plate and 29 indicates the rear hammer guide plate, which plates are mounted as at 30 and 31 to the side plates 2 and they are provided with V-shaped vertical guide grooves 32 and 33 respectively in which the hammer proper 52 has bearing.

Cross bars 35 of the cross head 55 extend through the vertical slots 34 in the side plates and their ends carry a pair of lever arms 40 fulcrumed at 41.

42 is a spring unit located between the upper ends of the levers 40 in cups 43 that engage recesses 44 in the levers for the purpose of pushing the upper ends apart and consequently forcing the lower ends of the levers apart. The lower ends 45 of the levers are slotted and through these

55

slots pass the forked rods 47, having threaded ends 50 for the reception of the bearing blocks 46 and the jam nuts 51, the bearing blocks 46 being convex to fit the concave lower ends 45 of the levers 40.

5 The rods 47 have their forks 48 pivoted at 49 to the hammer proper 52. It will be seen that the weight of the hammer which would tend to draw the lower ends of the levers 40 together, is counteracted by the spring unit 42 so that under normal 10 conditions the rods 47 lie substantially horizontal or in alignment with each other.

15 53 is the removable anvil die and 54 is the removable hammer die, these dies being held in dove-tailed slots in the respective members that carry the same.

The cross head 55 (or 56 as the case may be) is provided with bearing wings 39 to engage in the slots 34 with the rear edge of the support.

20 56 designates a modified cross head to take the place of the head 55, it having ears 57 to which the upper end of the connecting rod 25 may be pivoted, and it carries a pair of levers 58 between which is located a pull spring unit 59 whose ends 60 are connected to the levers and tend to force 25 the upper ends together and consequently force the lower ends apart.

25 In Figure 5 is shown another modification in which the levers 60 are pivoted together at 61 and carrying bearing ears 62 for connection with the 30 connecting rod 25, this form also employing a push spring like the spring 42.

The manner in which my invention operates is as follows:

35 The space between the dies is adjusted for the particular thickness of the beam or bar being worked upon by means of the lapped connection 26 of the connecting rod. Where thicker material is being hammered the connecting rod is lengthened at the joint 26 as will be clear to 40 those skilled in the art.

40 Upon throwing in the clutch the crank shaft will be turned rapidly (in practice about 400 to

450 revolutions per minute) thereby effecting a reciprocation of the hammer proper, causing it to strike the work. The rebound shocks of the hammer on striking the work are compensated for or absorbed by the spring 42 so that the rebound 5 shocks are smoothed out before being transmitted to the connecting rod 25.

The arms 60 are provided with a series of recesses 59a in which the lugs 59b may be located at different distances from the center 61 to allow 10 for adjustment of the stroke.

15 From the foregoing description, taken in connection with the accompanying drawings, it is thought the complete construction, operation, and advantages of my invention will be clear to those skilled in the art to which it relates.

What I claim is:

A power hammer comprising a base, a support mounted on the base, a crank shaft journalled in bearings on the support, an anvil unit mounted directly above the crank shaft, hammer guide-ways on the support, a hammer proper slidable toward and from the anvil unit in said guides provided above the anvil, a connecting rod between said crank shaft and said hammer proper 25 for reciprocating the hammer proper, said connecting rod lying to one side of said anvil and hammer and having offset portions, the ends of which line up with the vertical axis of the anvil and hammer, said connecting rod being composed 30 of two sections adjustably connected together for lengthening and shortening the same, and a flexible connection between said connecting rod and said hammer proper, said flexible connection comprising a cross head, lever members mounted 35 on said cross head, said lever members having upstanding arms, spring devices adjustably mounted on said upstanding arms for adjustment toward and from the pivots of said lever members, and connecting bolts between said lever members and said hammer proper.

JOHN SACK.
